Atty.

UNITED STATES PATENT OFFICE

AUGUST MERK, OF RADEBERG, GERMANY, ASSIGNOR TO PORZELLANFABRIK C. M. HUTSCHENREUTHER A. G., OF DRESDEN, GERMANY

ARTIFICIAL TOOTH

Application filed August 25, 1930, Serial No. 477,597, and in Germany April 18, 1929.

My invention relates to artificial teeth and more particularly to teeth which are adapted to be embedded in plastic material, for instance in caoutchouc, without the use of pins of precious metals and with or without a back plate.

It is an object of my invention to provide an artificial tooth which may be embedded in the plastic material so as to be anchored therein.

To this end I provide a cavity which extends from a seat at the upper end of the tooth to its back in combination with a web at the back of the tooth which bridges the cavity and a rib in the cavity which extends from the seat to the back of the tooth across the web.

By these means I provide a tooth which has a recess in its seat and two more recesses in its back, all connected with the cavity. The recesses which are entered by the plastic material, give the tooth a firm hold in the material and facilitate the securing of a back plate on the tooth.

In the drawings affixed to this specification and forming part thereof a tooth embodying my invention is illustrated diagrammatically by way of example.

In the drawings

Fig. 1 is an elevation of the tooth, viewed from its back,

Figs. 2 and 3 are sections on the lines II—II and III—III in Fig. 1, respectively, and

Fig. 4 is a section of the tooth, also taken on the line II—II in Fig. 1, showing a back plate on the tooth.

Referring now to the drawings, *a* is the tooth, with a seat *l* at the top and an edge *h* at the base, and *c* is a cavity which extends from the seat *l* to the back of the tooth. *d* is a web at the back of the tooth which bridges the cavity *c* and *b* is a central vertical rib which extends from a point slightly below the upper face of the web *d* through the cavity *c* and as far as the back of the tooth subdividing the cavity into two parallel passages. *f* is a horizontal face at the lower end of the rib which projects slightly beyond the back of the tooth and *e*, *e* are

grooves at the front end of the face and at both sides of the rib *b*.

The two parallel passages into which the cavity *c* is subdivided by the rib *b* extend from the seat *l* across and at right angles to the web *d*, and open at the back of the tooth. Any number of ribs *b* may be provided.

The opening of the cavity *c* in the seat *l* at the upper end of the tooth is particularly important for narrow teeth embedded in caoutchouc. The web *d* which extends substantially as far as the seat *l* increases the strength of the tooth.

The tooth which is preferably made of porcelain, can be used with and without a back plate. If it is used without a back plate the plastic material entering the cavity *c* and the passages at the sides of the rib *b* from the seat *l* and from the back anchors the tooth firmly. Additional hold is afforded by grooves *e*. It is not necessary that the face *f* should project from the back of the tooth but the tooth may be flat at the back if preferred.

Artificial teeth according to my invention are inserted in the plastic material in a simple and easy manner and effect a particularly durable connection with gum plates, artificial jaws and the like, and are cheap on account of their simplicity.

Referring now to Fig. 4, the tooth *a* is designed as described with reference to Figs. 1-3 but combined with a back plate *g*, which is fitted to the seat *l* at the upper end of the tooth and extends along its back as far as the projection of the face *f* on which it is abutted. Tabs *m*, *n* and *i* are provided for holding the back plate at the seat *l*, at the web *d* and the face *f*, respectively. The ends of the tabs *i* are hooked so as to enter the grooves *e*.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof.

I claim:—

1. An artificial tooth having a cavity in its seat, a plurality of longitudinal passages extending from said cavity to the back of the tooth, a bridge extending across said passages, a back plate, and means on said back plate for anchoring it in the cavity of said seat, on said bridge and in said passages.
2. An artificial tooth having a cavity in its seat, a plurality of longitudinal passages extending from said cavity to the back of the tooth, a bridge extending across said passages, a projecting face at the back of said tooth, a groove at the inner end of said face in each of said passages, a back plate, and means on said back plate for anchoring it on said seat, on said bridge, and in said grooves.

In testimony whereof I affix my signature.

20 AUGUST MERK.
